PERLEY R. GLASS, OF BROOKLINE, MASSACHUSETTS, ASSIGNOR TO UNITED SHOE MACHINERY CORPORATION, OF PATERSON, NEW JERSEY, A CORPORATION OF NEW JERSEY.

METHOD OF PERFORATING SHEET MATERIAL FOR THE RECEPTION OF EYELETS AND THE LIKE.

1,356,522.

Specification of Letters Patent. Patented Oct. 26, 1920.

Original application filed May 3, 1915, Serial No. 25,502. Divided and this application filed August 15, 1918. Serial No. 249,986.

To all whom it may concern:

Be it known that I, PERLEY R. GLASS, a citizen of the United States, residing at Brookline, in the county of Norfolk and 5 State of Massachusetts, have invented certain Improvements in Methods of Perforating Sheet-Material for the Reception of Eyelets and the like, of which the following 10 description, in connection with the accompanying drawing, is a specification, like reference characters on the drawings indicating like parts in the several figures.

This invention relates to methods of setting blind or invisible eyelets in sheet material such as the uppers of boots and shoes.

In setting blind or invisible eyelets by the methods heretofore employed, difficulties have been experienced in securing consistently the desired quality of finished work. 20 These difficulties include imperfections in the perforation of the work and imperfections in clenching the eyelet, particularly as regards the position of the upset portion of the eyelet between particular layers of the 25 work.

An object of the present invention is to provide, in setting blind or invisible eyelets, a method of operation insuring that the barrel of the eyelet will be clenched at the proper 30 plane in the upper, that is between predetermined layers of which the work is made, and that the perforating of the work may be carried out so that the resulting perforations shall be clean cut and properly located.

According to the preferred practice of the invention, one layer of the upper is perforated by means of a tubular punching tool while that layer is connected to and in face-to-face contact with the other layer or layers supported upon a suitable supporting 40 surface. The work is then fed laterally, preferably by the tubular punching tool until the perforation first formed is brought into alinement with a male punching tool 45 whereupon the other layer or layers are punched to complete a hole through the work, preferably by conjoint or telescopic action of the two tools. An eyelet is then inserted through one or more of the layers 50 and clenched, and for blind or invisible eyeleting the clenching may conveniently be done against the tubular punching tool

which for this kind of work would preferably remain in the work and have a clenching surface arranged to flare the eyelet between two contiguous layers of the work. 55 An important feature of the method just described is that the punching end of the tubular tool does not abut against any element that would dull it, and consequently it may be, and preferably is, sharpened to a keen cutting edge. Therefore the hole formed in the outer layer of the work will be cleanly cut instead of having a ragged or fuzzy edge as when punched by a tool that cuts 60 against a metallic block or plate and whose cutting edge is purposely made full so that it will not be chipped or turned.

Accordingly the invention, in one aspect, 70 consists in an improved method of perforating an article comprising two or more layers lying against each other by cutting through one of the layers beginning at one surface of the article and completing the hole by starting at the opposite surface and 75 progressing toward the first-mentioned surface.

When feeding the work is an important 80 step in the method a feature of the invention consists in executing the feeding motion after the beginning and prior to the completion of the hole-forming operation.

Considered otherwise the invention consists in punching a hole by two separate and successive operations, and in shifting the 85 work edgewise between said operations so as to complete the hole in registration with the place at which the eyelet is to be inserted.

Another feature of the invention consists 90 in utilizing the end face of a tubular punching tool to clench the eyelet, the said face preferably being the one by which the cutting or punching edge is formed, and being preferably frusto-conical and sufficiently 95 abrupt to flare the eyelet between two layers of the work without requiring the cutting edge to project from the work.

Still another feature consists in guiding 100 the eyelet into the hole by the male punching tool that works conjointly with the feeding tool to execute the second or final phase of the hole-forming operation. The male tool preferably, and as shown, is a part of

the eyelet-inserting tool, and accordingly one other feature consists in setting blind or invisible eyelets by the use of male and female hole-punching tools. Since the 5 male punch has a protruding tubular punching portion that extends into the work before and during the punching action of the male punch the latter merely forces the punchings through the bore of the female 10 punch without forcing the work along the exterior of the tubular portion. This is especially important in blind and invisible eyeleting because it is necessary to have the setting shoulder in a predetermined plane 15 of the work when the flaring of the eyelet is in progress.

In one of its important aspects, the invention consists in a method for setting eyelets in which the outer portion of the quarter is 20 punched while it is supported upon the lining portion and the lining portion is subsequently perforated in register with the hole thus formed.

In another of its aspects, the invention 25 consists in a method of setting eyelets in which a hole is formed in one portion of the quarter, the quarter relocated, and a second hole subsequently punched in another portion at the conclusion of the relocating operation.

These and other features of the invention 30 will be best understood and appreciated from the following description of one embodiment of the invention, reference being made to the accompanying drawing, in which,—

Figures 1, 2 and 3 are enlarged sectional views illustrating the successive steps of the method as carried out by one form of 40 apparatus, and

Fig. 4 is a perspective view of a portion of a shoe quarter having invisible eyelets set therein.

The method of operation to be herein described 45 may be conveniently carried out by a machine such as described in Letters Patent of the United States, No. 1,278,811, granted September 10, 1918, on an application of which this application is a division, but 50 it will be understood that it is not restricted to such a machine nor to the particular tools which are illustrated herein. For convenience, however, we will consider that the work is supported in its initial position 55 upon a punch block 10 and that it comprises a series of layers 12, 14 and 16 which, for simplicity of description, will be considered to be the outer leather, the stiffening member, and the lining respectively. The 60 punching and upsetting tool 20 is provided with a threaded shank 22 by means of which it may be supported on the operating plunger 24 of the machine. This tool is primarily a tubular punch having its lower end 26 tapered to form a cutting edge and inciden-

tally an upsetting surface as will presently appear. As shown in Figs. 1 to 3, the end 26 of the tool 20 is beveled or tapered in a concave manner, although it might be convexly tapered, and above the tapered portion 70 is a cylindrical portion 28. Above the portion 28 the tool is enlarged and provided with a threaded portion 30 upon which is adjustably held a stop 32 which comprises a 75 threaded nut.

The plunger 24 and tool 20 are so constructed and arranged that when the plunger is depressed the cutting edge of the tool will be forced through the outer portion 12 of a shoe quarter, or the upper layer of the work, 80 supported upon the cutting block 10, as shown in Fig. 1, and will enter slightly the material of the layer 14 beneath. In order to render this operation more accurate the stop 32 is so adjusted upon the threaded portion 30 of the tool 20 that the exposed length of the cylindrical portion 28 of the tool is substantially equal to the thickness of the portion 12 of the work. It will thus be seen that the lower layers 14 and 16 of the 90 work will constitute a yielding backing for the layer 12 which is to be perforated by the tool 20. As already pointed out the punching operation under these circumstances produces a very cleanly punched hole in the 95 upper portion 12 of the work.

The eyelet carrying set 40 is shaped at its upper end to receive the flange of the eyelet 42 to be inserted and with an upwardly projecting punching member 44 of such diameter as to enter the bore of the tubular punching tool 20. At its upper end the punching member 44 is beveled at 46 upon one side so that its punching action, in coöperation with the tubular punching member 20, will 100 be of a shearing punch and die nature. To insure more certainly the proper entering of the punching member 44 in the bore of the tubular punching member the opposite side of the upper end of the member is slightly 105 beveled. The punching member 44 occupies the position in the eyelet carrying set 40 of the usual center spindle and as such spindle it has the function of taking an eyelet from a raceway 50 and holding it in position during the upward movement of the eyelet carrying set. In the present construction the the punching member 44 also serves as a positive guide for directing the barrel of the eyelet through the lower portion of the work 110 and into engagement with the upsetting surface upon the end 26 of the tubular punching tool.

In practising my novel method with the apparatus herein illustrated, the shoe quarter is placed upon the work plate with the point at which the first eyelet is to be set above the cutting block 10 and in alinement with the tubular punching tool 20. The machine is then set in operation and the plun- 115

ger 24 depressed carrying the tubular punching tool through the upper portion 12 of the quarter and embedding its end slightly in the underneath portion 14 of the quarter.

5 Fig. 1 of the drawing shows the punching tool in this position. The tool 20 is then moved transversely toward the left feeding the entire quarter with it until it comes into a position in alinement with and above 10 the eyelet carrying set 40. At about this time the plunger carrying the set 40 is elevated and an eyelet supplied to the punching member 44 during the upward movement thereof. The punching member 44 then 15 counters the underside of the lower portion 16 of the quarter and in its upward movement enters the bore of the tool 20 shearing out a hole in the previously unperforated portions of the quarter. Fig. 2 illustrates 20 the position of the punching member 44 when it has partially entered into the bore of the tubular punch 20. As the upward movement of the eyelet carrying set 40 continues, the member 44 advances into the bore 25 of the tool 20 pushing the punchings ahead of it and at the same time guiding the end of the eyelet barrel through the lower portion of the quarter and into engagement with the upsetting surface of the end 26 of 30 the tubular punch. The end of the eyelet barrel is split by this surface and turned outwardly beneath the lower surface of the upper portion 12 of the work. When the tools reach their final position, as shown in 35 Fig. 3, the clenched end of the barrel is flattened down by the pressure upon it of the material of the upper portion 12 reinforced by the lower face of the stop 32.

The work herein illustrated comprises a 40 shoe quarter made up of an outer or leather portion 12 and a lining portion which in turn is made up of a stiffening strip 14 of canvas or similar material and a leather part 16. For convenience the invisible eye- 45 let will be described as being set in the lining part of the work, that is to say, with its flange against one surface of the part 16 and its clenched end against the oppositely disposed surface of the stiffening 50 strip 14 but it will be apparent that if desired the eyelet may be set in one layer only of the work. This would be accomplished if the tubular punch 20 were adjusted to pass through the intermediate strip 14 in its 55 punching operation.

In the foregoing description the operation of setting an invisible eyelet has been described, such an eyelet being one set in the lining portion of a quarter beneath the hole 60 formed in the outer or leather portion. The operation of setting a blind eyelet is similar in all respects except that the work is presented to the machine in an inverted position, that is to say, with the lining uppermost. 65 The eyelet then set will be disposed with its

flange upon the outer surface of the shoe and its clenched end within the lining portion so that only a hole for the passage of the lacing appears within the shoe.

Having thus described my invention, what 70 I claim as new and desire to secure by Letters Patent of the United States is:

1. That improvement in the art of shoe making which consists in punching the outer portion of a quarter while supported upon 75 the lining portion, perforating the lining portion, by a different operation, in register with the hole thus formed, inserting an eyelet barrel through the lining portion, and clenching it thereon. 80

2. That improvement in the art of shoe making which consists in punching a hole in the outer portion of a quarter, subsequently, and by another operation, punching a hole in the lining portion, in register with 85 the first said hole, and setting an eyelet in one of said holes.

3. That improvement in the art of shoe-making which consists in cutting a hole through the outer layer of a shoe-quarter 90 while said layer is against another layer of the quarter at the cutting locality, forming a hole through the other layer in registration with the first hole by progressing toward the outer layer while the two layers 95 are against one another, and setting an eyelet in the hole in the said other layer.

4. That improvement in the art of shoe making which consists in punching a hole by means of a tubular punch in the outer 100 portion of a quarter while said portion is yieldingly backed up by the lining portion, punching the lining portion by projecting a tool into the bore of the tubular punch, guiding an eyelet through the hole in the 105 lining upon said tool, and finally clenching the end of the eyelet barrel upon the tubular punching tool.

5. That improvement in the art of shoe making which consists in punching one portion of a shoe quarter, relocating the entire quarter, and punching another portion of the quarter in register with the first punching after relocating the quarter. 110

6. That improvement in the art of shoe making which consists in punching one portion of a shoe quarter, feeding the entire quarter, and punching another portion of the quarter in register with the first punching but after the feeding operation. 115

7. That improvement in the art of shoe making which consists in resting a plurality of superposed and connected layers of sheet material upon a support, moving a punch toward the support sufficiently to penetrate 125 one of said layers without causing the punch to touch the support, feeding the work in this condition to another position, and then completing the hole and inserting a fastener therein. 130

8. That improvement in the art of shoe making which consists in punching a hole in one portion of a shoe quarter, feeding the quarter to another position, punching another portion of the quarter in register with the first punching but after the feeding operation, inserting an eyelet in one of the punched portions, and finally clenching the eyelet between two portions of the work.
- 10 9. That improvement in the art of shoe making which consists in punching part way through a quarter from one side, forcing a combined work punching and eyelet guiding tool through the quarter from the opposite side, in register with the portion first punched, inserting into the quarter an eyelet surrounding said tool, and finally clenching the end of the eyelet between two layers of the work.
- 15 10. That improvement in shoe-making which consists in forcing a punching element part way through the work, moving said element laterally while it is in the work but before it has completed a hole there-through, completing the partially formed hole without completing the passage of the said element therethrough and setting an eyelet in the hole while the leading end of said element is in the hole.
- 20 11. That improvement in shoe-making which consists in forcing an acute annular cutting edge part way through the work to begin the forming of a hole in the work, completing the hole by forcing a waste portion of the work into the cutting element while the said cutting edge remains between the surfaces of the work, and setting an eyelet in the hole while the cutting edge is in the latter.
- 25 12. That improvement in shoe-making which consists in forcing an annular cutting edge and a setting shoulder part way through a piece of work comprising a plurality of layers, completing a hole through the work while maintaining the cutting edge and the setting shoulder between the outer surfaces of the work, and clenching an eyelet between two layers of the work by means of the setting shoulder.
- 30 13. That improvement in shoe-making which consists in forming a hole part way through an article of work by forcing an acute annular cutting edge into the article while sustaining the latter by one of two opposite surfaces thereof, completing the hole from one of said surfaces to the other while maintaining the cutting edge between the said surfaces, and setting an eyelet in the hole.
- 35 14. That improvement in shoe-making which consists in forming a hole part way through a piece of work by forcing an acute annular cutting edge part way through the work, then completing the hole and setting an eyelet therein while maintaining the cutting edge between the surfaces of the work.
- 40 15. That improvement in shoe-making which consists in forcing an annular cutting edge and a setting shoulder part way through a piece of work comprising a plurality of layers, and completing a hole through the work and clenching an eyelet between two layers thereof while maintaining the cutting edge and the setting shoulder between the outer surfaces of the work.
- 45 16. That improvement in shoe-making which consists in forcing the annular cutting edge of a tubular cutter part way through a piece of work, completing a hole through the work by punching a waste piece therefrom into the interior of the cutter while maintaining the said cutting edge between the surfaces of the work, guiding the barrel of an eyelet into the hole and onto that part of the cutter that is in the work, and clenching the eyelet.
- 50 17. That improvement in shoe-making which consists in forcing an annular setting shoulder through one layer of a plurality of superposed layers of work before a hole has been completed through all the layers, completing a hole through the work in coaxial registration with the setting shoulder while the latter is between the two outer surfaces of the superposed layers, and clenching an eyelet against the setting shoulder while the latter is in the hole.
- 55 18. That improvement in shoe-making which consists in forming a hole through a piece of work by beginning the formation at opposite surfaces of the work and completing it between said surfaces, and clenching an eyelet in the hole while an element of the hole-forming means is in the hole.
- 60 19. That improvement in shoe-making which consists in punching a hole part way through the work, moving one of the punching elements out of registration with the other, completing the hole by another combination of punching elements, and setting an eyelet in the hole.
- 65 20. That improvement in shoe-making which consists in punching a hole through the work, feeding the work after the beginning and before the completion of the hole-forming operation, and setting an eyelet in the hole.

In testimony whereof I have signed my name to this specification.

PERLEY R. GLASS.

It is hereby certified that in Letters Patent No. 1,356,522, granted October 26, 1920, upon the application of Perley R. Glass, of Brookline, Massachusetts, for an improvement in "Methods of Perforating Sheet Material for the Reception of Eyelets and the like," an error appears in the printed specification requiring correction as follows: Page 1, line 67, for the word "full" read *dull*; and that the said Letters Patent should be read with this correction therein that the same may conform to the record of the case in the Patent Office.

Signed and sealed this 4th day of January, A. D., 1921.

[SEAL.]

L. B. MANN,

Acting Commissioner of Patents.

Cl. 218—14.
